UNITED STATES PATENT OFFICE.

OTTO H. HOLDERER, OF SANDUSKY, OHIO.

DESIGN FOR A TAPPING-HAMMER.

SPECIFICATION forming part of Design No. 27,172, dated June 8, 1897.

Application filed April 19, 1897. Serial No. 632,869. Term of patent 7 years.

To all whom it may concern:

Be it known that I, OTTO H. HOLDERER, a citizen of the United States, residing at Sandusky, in the county of Erie and State of Ohio, have invented and produced a new and original Design for Tapping-Hammers; and I do hereby declare the following to be a full, clear, and exact description of the same, reference being had to the accompanying drawings, forming a part thereof.

My invention relates to a design for a tapping-hammer or beer-mallet.

It relates to the entire configuration of the hammer.

15 My invention relates particularly to the design for the tapping-hammer as illustrated in the accompanying drawings, in which—

Figure 1 is a perspective view of a tapping-hammer embodying my design. Fig. 2 is a 20 longitudinal section, and Fig. 3 a transverse section, of the same.

In the accompanying drawings the same reference-characters indicate the same parts of the invention.

25 The leading features of my design appear in the following description.

1 represents the cylindrical hammer-head, having a plane face 2, right-angular corners 3 3, an annular shoulder 4, a plane end 5, provided with the rounded edge 6. A longitudinal groove 7 extends the entire length of the head from the face 2 to the end 5, and 8 8 represent right-angular parallel arms, arranged on the rounded edge 6 and on each side of the longitudinal groove 7.

The socket or head 1 is made of cast malleable iron and the block which fits in it of a suitable hard wood to withstand the operation of tapping the keg.

Having thus fully described my invention, 40 what I claim as new and useful, and desire to secure by Letters Patent of the United States, is—

The design for a tapping-hammer, substantially as herein shown and described. 45

In testimony whereof I affix my signature in presence of two witnesses.

OTTO H. HOLDERER.
